To all whom it may concern:

Be it known that I, AGUSTA M. WARNER, a citizen of the United States, residing at San Francisco, in the county of San Francisco and State of California, have invented a new and original Design for Games, of which the following is a specification.

The invention relates to a new and original design for a game-board.

10 The object of the present invention is to provide an ornamental and attractive game-board.

15 The essential feature of the design resides in a rectangular game-board having a series of angularly-disposed parallel lines arranged on a circular surface bordered by a circle of seals interspersed with stars.

The figure of the drawing represents the

plan view of a game-board, showing my new design.

Referring to the drawing, 1 designates a rectangular game-board having a circular surface bordered by a ring 2 of seals of the different States interspersed with stars. On the circular surface within the border of States 25 are series of angularly-disposed parallel lines.

What I claim is—

The design for a game-board, as set forth.
